REFINING OF MINERAL OILS

Walter H. Rupp, Mountainside, N. J., assignor to
Standard Oil Development Company, a corpora-
tion of Delaware

Application July 2, 1941, Serial No. 400,721

5 Claims. (Cl. 196—7)

The present invention is concerned with the refining of mineral oils. The invention is more particularly concerned with the recovery of hydrocarbon gases which are evolved during the processing and storage of petroleum oils boiling in the motor fuel boiling range. The invention is especially concerned with a method of recovering these valuable hydrocarbon constituents in a manner that the hazard of an explosion is eliminated.

In the refining of mineral oils, particularly in the production and marketing of petroleum oils boiling in the motor fuel boiling range, it is necessary to store these oils in relatively large storage tanks into which a considerable quantity of air is drawn and from which an appreciable quantity of gas is expelled. The gases expelled in the "breathing" of the tank comprise a relatively high concentration of valuable hydrocarbon constituents. For example, the gases expelled from a tank in which a motor fuel having a vapor pressure in the range from about 450 to 600 mm. of mercury at 100° F., and in which the oil temperature is 100° F., comprise approximately 55% to 70% of hydrocarbon constituents. Since the atmospheric temperature passes through a cycle change every day, the loss in oil due to tank breathing over a relatively short time is appreciable. Furthermore, since the relatively lower boiling more valuable hydrocarbon constituents are initially lost, the quality of the remaining oil is also impaired.

In order to overcome these disadvantages it has been proposed that the gases which are exhaled be compressed and returned to the storage vessel. However, a process of this character is not satisfactory for the reason that although the gases removed from the storage vessel may be well outside the explosive limit, the explosion hazard is materially increased by compressing the gases in order to condense the same. I have, however, now discovered a process which may be readily adapted to the recovery of gases evolved from storage vessels in the above described manner, which entirely eliminates the explosion hazard now encountered. In accordance with my process, the vapors which are removed from the storage vessel and which contain a relatively high concentration of air are compressed to condense and recover the oil constituents. However, in order to eliminate the explosion hazard I segregate a portion of the lower boiling hydrocarbon constituents from the compressor condensate and pass the segregated stream into the exhaled va-

porous stream passing from the storage vessel to the compression zone.

The process of my invention may be readily understood by reference to the drawing illustrating an embodiment of the same. For the purpose of description, it is assumed that the petroleum oil stored is a petroleum oil boiling in the motor fuel boiling range. It is also assumed that the vessel comprises a conventional storage tank and that the vessel is approximately half full of the petroleum oil. As the atmospheric temperature drops as is normally the case during the night, the petroleum vapors in the upper part of the storage vessel are cooled and contract, resulting in fresh air being inhaled into the tank by means of valve or line 2. Furthermore, the temperature of the oil, particularly the temperature of the upper oil layer in contact with the vapors, is lowered, resulting in a lower vapor pressure and a further inhaling of fresh air. Thus, the extent to which the vapors in the upper part of the storage vessel, which comprise hydrocarbon constituents, contract is also a direct function of the vapor pressure of the oil. During the rise in atmospheric temperature, the vapor pressure of the oil increases, resulting in additional oil being vaporized. The vapors in the upper part of the storage tank also expand and are withdrawn from the storage tank by means of line 3. These vapors comprise a relatively large amount of air. In accordance with my process, these vapors are passed into compression zone 4 in which the same are compressed to the desired extent, withdrawn by means of line 5, condensed in cooling zone 6, and passed into separation zone 7. The uncondensed gases, substantially air, are withdrawn from separation zone 7 by means of line 8 and handled or disposed of in any manner desirable. The condensate is withdrawn from separation zone 7 by means of line 9 and passed into stabilization unit 10. Temperature and pressure conditions are adjusted to remove overhead by means of line 13 the lower boiling hydrocarbon constituents and to remove by means of line 12 the relatively higher boiling constituents which are returned to storage zone 1.

In accordance with my process, the lower boiling hydrocarbon constituents removed by means of line 13 are introduced into the stream passing from the storage zone to the compression zone. Under certain conditions, depending upon the composition of the vapors passing from the storage zone to the compression zone, it might be desirable to utilize only a portion of the vapors removed overhead from zone 10. This condition

may exist when the temperature cycle is relatively high, resulting in the expelling of a relatively large quantity of hydrocarbon vapors. If this operation be desirable, the remaining portion of the vapors removed overhead from zone 10 are removed by means of line 11 and handled or disposed of in any manner desirable. Under certain conditions as, for example, when a relatively small amount of hydrocarbon vapors are evolved from the storage zone, it may be desirable to add a quantity of relatively low boiling hydrocarbon constituents secured from an external source which are introduced into the system by means of line 15.

The process of the present invention may be widely varied. The invention essentially comprises segregating relatively low boiling hydrocarbon constituents from the condenser condensate and introducing these segregated hydrocarbon constituents into the stream flowing from the storage zone to the compression zone. The temperature in the storage zone will vary considerably but will generally vary in the range from about 35° F. to about 110° F. The pressure on the zone will vary in the general range from about -10 inches of water to 70 pounds per square inch gauge pressure, depending upon the nature of the stock stored. The compression zone will be operated at a pressure between about 100 pounds to 500 pounds per square inch gauge, and generally operated at a pressure in the range from about 250 to 400 pounds per square inch gauge. The temperature maintained in the separation zone may vary considerably but will generally be in the range from about 40° F. to 120° F. For example, when the storage oil comprises a petroleum oil boiling in the motor fuel boiling range, the temperature maintained in the compression zone is generally in the range from about 60° F. to about 80° F.

The amount of relatively low boiling hydrocarbon constituents circulated to the compression zone along with the feed gases to the compression zone will vary considerably depending upon the character of the vapors evolved. In general, the amount circulated is to increase the hydrocarbon constituent concentration so that it will be well above the explosive limits. I have found that the amount of relatively low boiling hydrocarbon constituents recycled to the compression zone is in the range from about 5% to 50% by volume, preferably between 15% to 30% by volume, based upon the total tank vapors.

In order to illustrate my invention further, the following example is given which should not be construed as limiting the same in any manner whatsoever.

Example

The vapors evolved from a storage tank in which motor gasoline is stored at 100° F., which gasoline has a vapor pressure of 540 mm. of mercury, comprise about 35% air by volume. The remainder comprises hydrocarbon fractions which are recoverable.

The lower explosive limit for the hydrocarbons contained in the vapors in equilibrium with the gasoline is about 1.5 mol percent, while the upper limit is about 8.0 mol percent. Thus, it is desirable to maintain the concentration of hydrocarbons without the range of 1.5 to 8.0 mol percent.

In recovering as liquid the valuable vaporous hydrocarbon fractions by compression and subsequent cooling, the residue gas stream will ordinarily increase in air content and enter the ex-

plosive limit range. However, I have discovered that this may readily be avoided without decreasing gasoline recovery providing the liquid condensate be segregated and a portion of the same recycled as described. This is readily apparent by the following data in which in one operation recycle of segregated condensate constituents was not employed, while in a second operation recycle of these constituents was employed.

Operation 1 (Recycle of segregated constituents not employed)

	Tank vapors	Residue gas after compression	Recovered gasoline after compression
Temperature	100° F.	70° F.	70° F.
Pressure	Atmos.	380# ga.	380# ga.
Analysis:			
Air	35% (mol)	93% (mol)	
Propane	40	6 ¹	61% (mol)
Pentane	15	1 ¹	23%
Hexane+	10		16%
Total	100	100	100
Percentage on tank vapors	100%	35%	65%

¹ 7% hydrocarbon falls in explosive limit and is unsafe.

Operation 2 (Recycle of segregated constituents)

	Tank vapors	Intermediate recycle gas stream	Residue gas after compression	Recovered gasoline after compression and stabilization
Temperature	100° F.	100° F.	70° F.	70° F.
Pressure	Atmos.	Atmos.	350# ga.	350# ga.
Analysis:				
Air	35% (mol)	83% (mol)		
Propane		100%	11 ¹	
Butane	40		5 ¹	61% (mol)
Pentane	15		1 ¹	23% (mol)
Hexane+	10			16% (mol)
Total	100		100	100
Percentage on tank vapors	100%	25%	65%	35%

¹ 17% hydrocarbon well outside explosive limit and is safe.

From the foregoing it is apparent that by following the process of the present invention, the composition of the gases after compression is maintained well above the explosive limit without decreasing the recovery of gasoline fractions.

What I claim as new and wish to protect by Letters Patent is:

1. In the handling of low boiling hydrocarbons in admixture with substantial quantities of air produced in the breathing of gasoline storage tanks, the improvement which comprises counteracting the explosive tendency of said mixture by adding thereto additional air-free vaporized low boiling hydrocarbons in quantity sufficient to render said mixture explosion proof, compressing the resulting hydrocarbon-enriched mixture under conditions to condense hydrocarbons therefrom, and returning said condensed hydrocarbons to the storage tank.

2. Process according to claim 1, in which the added hydrocarbons are secured by condensing hydrocarbons from the mixture of hydrocarbons and air, removing uncondensed gases from the condensate, segregating from the condensate relatively lower boiling hydrocarbons and adding said hydrocarbons to said gas mixture.

3. Process according to claim 1, in which the quantity of hydrocarbons added is within the

range of 5 to 50% by volume based upon the volume of vapors evolved from the tank.

4. In the handling of the vapors of low boiling hydrocarbons in admixture with substantial quantities of air produced in the breathing of gasoline storage tanks, the improvement which comprises compressing the vapor-air mixture, cooling the compressed mixture to form a condensate, separating air therefrom, fractionating the condensate to produce vapors of low boiling hydrocarbons and a residual hydrocarbon liquid,

passing said vapors of low boiling hydrocarbons into the vapor-air mixture from the tank in quantity sufficient to place the same outside the explosive range prior to compression of the mixture, and returning the residual hydrocarbons to the tank.

5. Process according to claim 4, in which the quantity of hydrocarbons added is within the range of 5 to 50% by volume based upon the volume of vapors evolved from the tank.

WALTER H. RUPP.
